US0D1021063S

(12) **United States Design Patent** (10) Patent No.: **US D1,021,063 S**
(45) Date of Patent: ** Apr. 2, 2024

(54) **INSERT FOR A DIVING MASK**

(71) Applicant: **Kirby Morgan Dive Systems, Inc.**,
Santa Maria, CA (US)

(72) Inventors: **Connie Lyn Morgan**, Santa Maria, CA
(US); **Peter Mark Ryan**, Santa Maria,
CA (US); **Trent Matthew Schultz**,
Goleta, CA (US); **Michael Francis
Ward**, Panama City Beach, FL (US)

(73) Assignee: **KIRBY MORGAN DIVE SYSTEMS,
INC.**, Santa Maria, CA (US)

(**) Term: **15 Years**

(21) Appl. No.: **29/804,197**

(22) Filed: **Aug. 18, 2021**

(51) LOC (14) Cl. **24-01**

(52) U.S. Cl.

USPC **D24/110.5**

(57) **CLAIM**

The ornamental design for an insert for a diving mask, as shown and described.

DESCRIPTION

FIG. 1 is a front perspective view of our insert for a diving mask;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines shown in the drawings illustrate portions of our insert for a diving mask that form no part of the claimed design.

1 Claim, 6 Drawing Sheets
